DESIGN FOR A MULTIPLE BAKE PAN UNIT
OR SIMILAR ARTICLE

Joseph G. Jackson, Oak Park, Ill., assignor to The
Edward Katzinger Company, Chicago, Ill., a cor-
poration of Illinois

Application June 20, 1940, Serial No. 93,131

Term of patent 14 years

To all whom it may concern:

Be it known that I, Joseph G. Jackson, a citizen of the United States, residing at Oak Park, in the county of Cook and State of Illinois, have invented a new, original, and ornamental Design for a Multiple Bake Pan Unit or Similar Article, of which the following is a specification, reference being had to the accompanying drawing, forming a part thereof.

Figure 1 is a perspective view of a multiple bake pan unit or similar article, showing my new design, it being understood that the frame shown in full lines is continued throughout the perimeter of the article.

Figure 2 is an enlarged fragmentary perspective view of the article, being shown broken away for convenience of illustration and in order to show a portion in section.

The dominant feature of the design resides in the portion shown in full lines.

I claim:

The ornamental design for a multiple bake pan unit or similar article, as shown and described.

JOSEPH G. JACKSON.
